UNITED STATES PATENT OFFICE.

FERDINAND C. H. MÜLLER, OF SANDUSKY, OHIO, ASSIGNOR, BY MESNE ASSIGNMENTS, TO MYER PRUSSIAN, OF DETROIT, MICHIGAN.

SLOTTING MACHINE.

Application filed November 25, 1921. Serial No. 517,480.

To all whom it may concern:

Be it known that I, FERDINAND C. H. MÜLLER, a citizen of the United States, and a resident of Sandusky, in the county of Erie and State of Ohio, have made an Invention Appertaining to a Slotting Machine; and I do hereby declare the following to be a full, clear, and exact description of the invention, such as will enable others skilled in the art to which it appertains to make and use the same, reference being had to the accompanying drawings, and to the characters of reference marked thereon, which form a part of this specification.

15 My invention has for its object to provide a slotting die and means coacting with the die to permit successive operations of the die. In connection with my invention I provide means for attaching the die and its 20 associated parts to a press of any suitable form. The invention particularly has for its object to provide a means for efficiently slotting or castellating nuts and to this end I provide a floating die which will readily 25 adjust itself to variations commonly existing in connection with nut blanks, and also means for ejecting the slugs formed in forming the slots of the nuts and for removing the nuts. I also provide automatic means 30 for moving the nut into different positions in order that the sequential operations may be performed upon it.

The invention may be contained in machines and devices of different forms, and 35 for different purposes. To illustrate a practical application of structures containing my invention I have selected one of such structures as an example of such structures, and shall describe it hereinafter. The structure selected for purposes of illustration is 40 shown in the accompanying drawings.

Figure 1 of the drawings illustrates a front view of the device containing my invention and a front view of the ram of the 45 press to which the device is connected. Fig. 2 is a longitudinal sectional view of the device illustrated in Fig. 1. Fig. 3 is a rear view of the device and of the ram, a supporting bracket being shown removed in order that certain parts may be illustrated. Fig. 4 illustrates a supporting bracket used 50 in connection with the device. Fig. 5 is a top view of the device.

1, in Figs. 1, 2 and 3, is the ram of any 55 suitable plunger press and which is connected

to the driving mechanism in any suitable way, movement of the ram being caused by a trip of any well known character. A punch 2 is connected in any suitable way to the ram 1, as by the clamping plate 3 and the clamping screws 4. The punch 2 may extend above the plate 3 and be secured in the adjustable sleeve 5. The punch 2 has preferably an inclined, slightly curved punching surface and cutting edge 6. The 60 inclination of the edge and the surface is downward from the back edge or side of the punch so that the blank is struck first near the center or axis of the punch and is sheared between the die and the punch. The 65 radius and the inclination of the curved surface and the edges of the punching area causes the blanks to be pushed into position when the punch strikes the edges of the blanks as will appear hereinafter.

75 The punch 2 coacts with the die 7 which is supported on the bed of the press. It is supported within a die housing 8 that is connected in any suitable way to the bed. The die 7 has a stem of considerable length, one 80 end of which is secured in the bracket 9 by means of the bolt 10 that extends through the upper end of the bracket and is provided with a dowel pin at its lower end which enters a hole in the end of the stem 85 of the die. The end of the stem of the die may be provided with a bushing 11 which forms a bearing bushing between the end of the stem of the die and the bracket. The stem extends through an opening 12 located 90 in a spindle 13 that is supported in the housing 8. A considerable clearance exists between the surface of the opening 12 and the die and its stem to allow a slight movement of the die. The die will nevertheless be 95 maintained coaxial with the opening 12 when released from the pressure of the punch.

The die 7 is of a size that will readily enter the cylindrical opening of the articles 100 to be operated upon, such as the holes of the nuts to be castellated or slotted. The end of the die is provided with a slot 14 into which the end or a portion of the end of the punch 2 enters. The upper edge of the slot 105 14 forms a shearing edge that coacts with the shearing edge of the punch 2 and thus a cut or slot may be produced at one point and on one side of the nut or other article when the punch penetrates into the die.

110

90

95

105

110

The die and the stem are provided with the hole 15 that extends longitudinally through the die and the stem. An ejector rod 16 is located in the hole 15 and terminates in proximity to the slot 14. The rear end of the rod 16 is connected to the lever 17 by means of the block 18 and the pins or stubs 19. The stubs are located in the slot 20 formed at the end of the lever 17 so as to permit angular movement of the lever and yet cause longitudinal movement of the rod 16. The lever 17 is given short angular movements and so as to cause the end of the rod 16 to pass through or beneath the slot 14 by means of the cam plate or bracket 21 that is secured to the ram 1. The lever 17 is provided with a roller 22 which is located in an angular slot 23 formed in the cam plate 21 and each time the ram descends the rod 16 is pushed into and drawn out from under the slot 14. This also occurs each time the ram is raised. The slugs that are severed from the nut or other article by the operation of the punch 2, ordinarily gather in succession in the slot 14 and are pushed down in subsequent operations of the punch into the hole 15 in front of the rod 16. However, to insure that the lower-most slug is removed from the die and thus insure clearance or room for operation of the punch the rod 16 is operated upon during each of the movements of the ram.

The spindle 13 is rotatively supported in the housing 8. A bushing 24 may be located intermediate the spindle 13 and the housing 8 for bearing purposes. The spindle 13 is provided with a holder 25 which forms a basket or pocket for receiving the articles to be operated upon by the punch and the die. When the device is used for castellating nuts the interior of the pocket 25 has a shape substantially that of the exterior of the nut, that is, when the nut to be slotted is a hex it has a hexagonal shaped recess. When the nut is a square the recess of the holder is square. The holder 25 is secured in the spindle 13 by means of the screws 26 and by dowel pins 27. The holder 25 fits over the end of the die 7 and is provided with an opening substantially the same size as the opening 12 and to afford the same clearance between the stem of the die and the holder that is formed between the stem of the die and the spindle 13.

The blanks are inserted over the die 7 and into the recess 28 of the holder 25. When the punch 2 is depressed so as to coact with the die 7 to shear the object, the object is supported by the lower side of the holder 25 which is supported by the spindle 13 and the pressure is transmitted directly through the bushing 24 to the housing 8. Also the die 7 by reason of its long stem is permitted to rest on the lower side of the hole in the object and thus a solid support is provided

for the die 7 during the shearing operation. The elasticity of the stem causes its return to its coaxial position when the punch is raised. This forms a floating die that readily permits insertion of the blanks in position and yet gives a solid foundation for the die during the shearing operation. 70

The holder 25 is provided with a plurality of slots 29 and the bushing 24 is provided with a slot 30 through which the punch 2 may pass to enter the slot 14 of the die 7. The slots 29 are caused to register with the slot 30 and be placed in alignment with the slot 14 in succession by step by step movements of the spindle 13. 75

The spindle 13 is rotated by the operation of the pawl 31 that operates upon the ratchet 32 which is keyed to the spindle 13 by the key 33 and also secured by the lock nut 76. The ratchet 32 is located in the housing 34 that is freely rotatable about the sleeve 13. The housing 34 is supported on shoulders of the ratchet 32 and is closed by means of the cover 35 whereby the ratchet 32 is enclosed within the housing 34 except for the opening 36 formed in the sides of the housing through which the spring 37 extends to press the pawl 31 against the ratchet 32. The pawl is pivotally connected to the housing 34 by the pivot pin 38 and moves therewith when rotated about the axis of the spindle 13 and with the housing 34. 80

The housing 34 is rotatively moved on the ratchet 32 by means of the link 39 which is connected to the ram 1 by the screw 40 and to the housing 34 by the stud 41. When, therefore, the ram descends the pawl 31 is moved with the housing 34 and is held against the ratchet 32 by the spring 37. On the return movement of the ram 1 the pawl 31 catches the ratchet 32 and moves the spindle 13 one step forward so as to bring the slots 29 sequentially in alignment with the slot 30 and the slot 14, whereby portions of the nut placed in the holder 25 will be placed in proper position to be acted upon by the punch 2 and the die 7. If the object to be punched is a hexagonal nut the ratchet 32 will be provided with six teeth on its circumference to cause the proper placement of the holder and consequently of the nut. 105

When the punch 2 and the die 7 are operated the object is securely held in position by means of a spring-pressed lock 42 that engages in slots formed in the periphery of the index plate 43 and which is automatically unlocked by the operation of the ram 1 during the shifting of the article to its subsequent position. The housing 34 is provided with a projecting cam 44 and the lock 42, which is slidably supported in gibs 45 and is spring pressed by the springs 50, is provided with a latch 46 having the roller 47. The latch 46 is pivotally supported in a recess formed in the locking bar 42 which 110

thus provides a limiting stop 48 formed integral with the bar 42. The latch 46 is yieldingly pressed against the stop 48 by means of the spring 49. When, therefore, 5 the cam 44 is given oscillatory movements by the operation of the ram 1 it strikes the roller 47 when moving in one direction so as to raise the latch 46 and permit the cam 44 to pass the roller without causing the spindle 10 13 which is keyed to the index plate 43 to become unlocked, but when the cam 44 is swung downward, that is, when the ram 1 is raised, the cam 44 will operate upon the roller 47 to push the lock 42 away from the 15 index plate and thus unlock the spindle 13 and permit the pawl 31 to rotate the spindle 13 a part of the angular movement produced in the pawl 31 by the operation of the link 39 and the ram 1. When, therefore, 20 the ram 1 descends it carries the pawl 31 well below the succeeding tooth of the ratchet 32 while the spindle is being held by the lock 42 and on its return movement the spindle is rotated 60° when the object 25 operated upon is a hex nut.

When the required number of step by step movements have been performed in the spindle 13 so as to permit the required number of operations upon the object, the object 30 may be automatically ejected by means of the ejecting rods 51 that are located in holes formed in the spindle 13. The rods 51 are connected to a collar 52. The collar 52 is 35 spring pressed against the bracket 9 by means of the springs 53. The rods 51 and the collar 53 are operated by the forked bar 54 that is pivotally supported in the ears 55. The fork 54 has fingers that press against the collar 52 to push the rods 51 40 against the action of the springs 53 into the recess 28 of the holder 29 and thus cause the article to be ejected therefrom during the upward stroke of the ram succeeding the downward stroke that completed all of the 45 operations to be performed on each individual nut. The operation of the forked bar 54 to eject the nut is caused by the cam block 56 having the cam surface 57 and which is mounted on the slideable bar 58. 50 The cam is secured in position to the housing 8 by means of the screws 59 located in slots 60 formed in the bar. The bar 58 is yieldingly held in one position by the spring 61 which is connected between one of 55 the pins 59 and a post 62 located on the bar 58. The index plate 43 is provided with a projection 63 that engages an insert 64 located on the bar 58 and so positioned that upon the completion of the operations on 60 the object it will cause the bar 58 to be moved against the tension of the spring 61 and cause the cam block 56 to operate upon the roller 65 located on the lower end of the forked bar or lever 54. This will cause 65 the bars 51 to be moved forward in the holder 25 and eject the object from within the holder. A succeeding nut or object may then be placed in the holder and the operations will proceed as before. If desired the press may be tripped so as to cause momentarily cessation of the operations of the press. 70

In starting, the ram may be caused to be operated through the manipulation of any of the well known controlling tripping mechanisms. For purposes of illustration I have indicated merely a bar 66 that extends upwards toward the crank shaft of the ram which may be connected directly or indirectly to the key that connects the crank shaft with the fly wheel of the press and which is operated by longitudinal movements of the bar 66. The bar 66 is connected to a lever 67 that is pivoted to the housing 8 by means of the pivot pin 68. A cam 69 operates upon the end 70 of the bar to cause the bar to tilt and to draw the lever 66 downward. The cam 69 may be connected to a handle or arm 71 to raise the end 70 of the bar 67. The handle 71 and the cam 69 are 80 supported on the rod 72 which is located in ears 73 connected to the housing 8 or forming a part of the housing 8. When the rod 66 is pulled down by the operation of the lever 67 it draws a catch 74 beneath the end of the bar 58. The catch 74 and the end of the bar 58 are provided with inclined cam surfaces that coact to cause the bar 58 to be pushed forward a short distance and the cam 74 passes beneath the lower edge of the bar 58 and is caught and held thereby because of the spring 61 operating to permit the movement of the bar 58 and also operating to draw the bar 58 so as to engage the catch 74. 85 This operates to hold the lever 67 down and consequently to hold the rod 66 down, which maintains the key of the press in position to cause the sequential operations of the ram 1 and thus to cause the punch 2 to perform the required number of operations upon the 90 article. During these operations the spindle 13 is stepped around by the required number of short angular movements until the bar 58 is operated by the projection 63 which releases the lever 67 and raises the rod 66 to stop the operations of the press. The movements of ejection and of the parts that control the operations of the press may be performed during the time that the pawl 31 moves from its lowermost position to near the subsequent tooth of the ratchet that it is about to engage. For this reason the pawl is caused to move to a point well below the succeeding tooth of the ratchet 32. 95

The spindle 13 is secured in position in the housing 8 and rotation thereof is frictionally resisted by means of the spring-pressed shoes 77 that are located in a channel 78 formed in the spindle 13. Pins 79 extend through the housing 8 and are pressed against the shoes 100 105 110 115 120 125 130

77 by the springs 80 that are held in position by means of the threaded studs 81, feet 82 and the thumb nuts 83 which are screwed onto the studs 81. The pressure of the shoes 5 77 may be regulated by the position of the thumb nuts 83 on the studs 81. This will prevent any movement of the spindle 13 during the drawing of the pawl 31 over the ratchet 32 while the spindle 13 is unlocked by 10 the lock 42, and thus prevent the spindle 13 from being dragged rearwardly by the pawl. The spindle is retained in position by the pins 79 that extend through the housing and into the shoe which is located in the 15 channel 78 formed in the spindle 13. The spindle may thus be easily removed from the housing 8 by merely withdrawing the pin 79.

Different sized nuts or different sized objects, or objects of different shapes, may be operated upon by changing the holder and, if necessary, changing both the holder and the die. The holder may be easily removed by unscrewing the screws 26 and inserting 20 the desired size or shape holder. Also the die 7 may be easily removed by unscrewing the screw 10. In this way different sized articles may be operated upon in the machine.

I claim:

30 1. In a slotting machine for slotting hollow objects, a punch, a floating die co-acting with the punch and located within the object, and means located within the die for ejecting the parts sheared from the object from within the die.

2. In a slotting machine for slotting hollow objects, a spindle having means for holding the object to be operated upon, a die extending through the spindle and into 40 the objects held by the spindle and movable with respect to the spindle, a punch operating in a direction transverse to the axis of the spindle and coacting with the die to shear the objects, means for causing step by

step movements of the spindle, and an ejector 45 rod located within the die for ejecting the portions sheared by the punch and the die from within the die and the object.

3. In a slotting machine for slotting hollow objects, a punch, a floating die co-acting with the punch and located within the object, and a reciprocating means located within the die for ejecting the parts sheared from the object.

4. In a slotting machine for slotting 55 hollow objects, means for supporting the bed, a punch, a stem rigidly connected to the bed at one end of the stem, a die located at the other end of the stem for receiving the objects and coacting with the punch to 60 shear the wall of the hollow objects and a reciprocating means located in the stem and die for ejecting the parts removed from the hollow objects by the punch.

5. In a slotting machine for slotting 65 hollow objects, a punch, a floating die co-acting with the punch and located within the object and a reciprocating means located within the die for ejecting the parts sheared from the object. 70

6. In a slotting machine for slotting hollow objects, a punch, a floating die co-acting with the punch and located within the object and a rod located in the stem and the die for removing the parts sheared 75 from the hollow objects from within the die.

7. In a slotting machine for slotting the edges of the hollow objects, a punch having inclined curved cutting edges for shearing progressively from the edge of the hollow 80 objects inward, a die coacting with the punch and located within the hollow objects and a reciprocating member located within the die for ejecting the portions sheared from the hollow objects from within the die. 85

In testimony whereof, I have hereunto signed my name to this specification.

FERDINAND C. H. MÜLLER.
